UNITED STATES PATENT OFFICE.

EMIL BERNER AND BERGER BERNER, OF CALUMET, MICHIGAN.

WASTE-RETAINER.

1,291,733.

Specification of Letters Patent.

Patented Jan. 21, 1919.

Application filed July 31, 1917. Serial No. 183,755.

To all whom it may concern:

Be it known that we, EMIL BERNER and BERGER BERNER, citizens of the United States, residing at Calumet, in the county of Houghton and State of Michigan, have invented certain new and useful Improvements in Waste-Retainers, of which the following is a specification.

This invention relates to waste retainers and more particularly to a device adapted to hold a packing of oil saturated waste in a journal box for preventing displacement of the waste and thus facilitating proper oiling of the journal.

Another object of the invention is to provide a device of this character constructed from a single length of wire designed to be snugly held within the journal or oil box and retained in position by the top or cover 20 of the box whereby the oil saturated waste may be maintained in packed formation.

The invention also aims at the provision of a bent wire grille designed to have portions thereof project into a mass of waste 25 to retain a hold on the same so that the waste will be prevented from moving up in front of the oil box and thereby leave the journal improperly lubricated.

A further object of this invention is the provision of a waste retainer which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawings, wherein is illustrated the preferred form of my invention, in which;

Figure 1 is a plan view of the device showing the same mounted in a journal box, the latter being shown diagrammatic.

Fig. 2 is a fragmentary longitudinal section of the same.

Referring to the drawings, wherein is illustrated the preferred form of my invention, and in which like numerals of reference indicate corresponding parts throughout the several views, a single strand of wire is bent to form a grille 1 and the same consists of a series of loops 2 the ends of which are substantially square as indicated clearly in Fig. 1 of the drawing so that relatively short bars 3 are formed at the end of each

loop. It will be understood that this grille may be of any desired width and may consist of any desired number of loops according to the size of the journal box or the quantity of waste to be retained therein. This grille is formed intermediate the ends of the wire so that two comparatively long portions are provided at each end.

By bending these extended end portions of the wire upon themselves, the retaining loops 4 are provided and the loops then extend for a short distance where the wire is brought into engagement with the ends of the grille so that double portions 5 are formed to add strength to embrace the loops. Each end of the wire is then twisted around the corresponding end loop as indicated at 6 and from this point the ends of the wire are projected at right angles above the plane of the grille and the terminals of the wire formed into fingers 7 which engage the cover A of the oil or journal box B.

A quantity of waste is packed in the journal or oil box B in the usual manner and is saturated with a quantity of oil or grease for the purpose of lubricating the journal C. The grille 1 bears upon the waste and the ends of the loops 2 are bent downwardly so that the bars 3 are embedded in the waste to obtain a firm grip on the same. These downwardly bent portions of the loops thereby form claws 8 to retain the waste in proper position. Each end loop 3', however, is bent downwardly to a greater distance to form the long claws 9 obtaining a further and more effective grip on the waste to prevent lateral movement thereof in the journal box.

From the foregoing it will be observed that a very simple and durable waste retainer has been provided, the details of which embody the preferred form. We desire it to be understood, however, that slight changes in the minor details of construction may be made without departing from the spirit of the invention or the scope of the claims hereunto appended.

We claim:

1. A waste retainer comprising a grille constructed from a single length of wire bent into a series of loops, each of the latter having their ends curved to form claws, and means formed on the ends of the wire to retain the grille in position.

2. A waste retainer constructed from a single length of wire bent intermediate its

2
ends into a series of laterally spaced loops having their end portions substantially straight, the end portions being bent to form claws whereby the said straight portions 5 will be embedded in the waste, and means extending above the said loops to hold the latter in engagement with the waste.

3. A waste retainer constructed from a single length of wire bent intermediate its 10 end into a series of laterally spaced loops having their end portions substantially straight, the end portions being bent to form claws whereby the said straight portions 15 will be embedded in the waste, and means extending above the said loops to hold the latter in engagement with the waste, the said means including right angularly bent ends of the wire projecting above the loops.
4. A waste retainer constructed from a single length of wire bent intermediate its 20

end into a series of laterally spaced loops having their end portions substantially straight, the end portions being bent to form claws whereby the said straight portions 25 will be embedded in the waste, and means extending above the said loops to hold the latter in engagement with the waste, the said means including right angularly bent ends of the wire projecting above the loops, 30 portions of the said wire being extended to one side of the loops and bent upon themselves and twisted about the outermost loops.

In testimony whereof they affix their signatures in presence of two witnesses.

EMIL BERNER.
BERGER BERNER.
